Filed July 6, 1966, Ser. No. 563,233
6 Claims. (Cl. 339—272)

ABSTRACT OF THE DISCLOSURE

An improved clamping screw including a threaded shank having an undercut groove and retaining flange at one end, and a spring metal pressure pad mounted on the one end of the screw. The pressure pad includes a pressure wall disposed in front of the flange, and laterally deflectable mounting arms positioned in the groove having camming portions located at their ends to retain the pressure pad on the screw.

This invention relates to improvements in electrical wiring terminals, and more particularly, to providing in clamp-type terminals improved pressure pad means.

One of the known prior art terminal constructions for connecting electrical conductors to one another or to the contacts of electrical wiring devices is the clamping arrangement wherein the bared end of an electrical conductor is inserted into a clamp-type terminal and a screw, which is threadedly engaged in one wall of the clamping device, is brought to bear on the wire thereby urging it towards an opposed clamping wall. A serious problem exists when this type of terminal clamping screw is employed, namely the exertion of an undesirable twisting force on the bared cable wire which is particularly harmful to bared stranded wires. The leading or cable contacting end of the clamping screw comprises a pressure transmitting surface which exerts a desirable crushing force on the electrical conductor; however, it also exerts on the electrical conductor an undesirable twisting force which has a tendency to cause some of the stranded wires to be pulled away from the body of the wires which wires may become severed. In use, these wire fragments may cause short circuits or have other deleterious effects. To eliminate this undesirable twisting force on bared stranded wires of the electrical conductors, prior art clamping screws have been provided which transmit to the electrical conductors only compressive forces through non-rotating pressure pads permanently secured to the leading ends of the usual clamping screws. Although these known improved clamping screws have solved a serious problem, they are undesirable from a commercial viewpoint as special tools and skills are required to mount and stake or rivet the pressure pads permanently upon the clamping screw.

Accordingly it is the object of the present invention to provide an improved electrical wiring terminal, particularly of the clamping type, having a unique clamping screw upon which may be mounted a non-rotating pressure pad which may be made of spring metal, may be readily manufactured and which may be readily manually mounted upon the unique clamping screw.

To accomplish this object in one form, an improved clamping screw is provided comprising: a threaded shank having a head at one end, and a plain undercut portion at the other end, said plain undercut portion terminating in an enlarged retaining flange of smaller diameter than said shank; and a spring metal pressure pad mounted on said shank and including a pressure wall disposed in front of said flange and a mounting means therefor operatively associated with said undercut portion so as to

2

be mountable thereon by relative lateral movement of said mounting means and said undercut portion.

Other objects and further details of that which I believe to be novel and my invention will be clear from the following description and claims taken with the accompanying drawing, wherein:

FIG. 1 is a plan view taken substantially along line 1—1 of FIG. 2 showing an electrical wiring terminal of the clamp type constructed in accordance with the present invention with portions of conductor wire attached;

FIG. 2 is a front elevational view taken substantially along line 2—2 of FIG. 1 showing a conductor wire clamped by a pressure pad;

FIG. 3 is an elevational view taken substantially along line 3—3 of FIG. 2;

FIG. 4 is an enlarged perspective view showing the pressure pad alone removed from the terminal assembly;

FIG. 5 is a perspective view of the improved clamping screw.

With particular reference to FIGS. 1 and 2, an electrical wiring terminal embodying the present invention is shown in use connecting the electrical cables 10, whose bared stranded conductor wire ends 12 have portions introduced to and disposed within the tubular metal terminal block 14. The clamping screws 16, upon whose ends are mounted pressure pads 18 made entirely of spring metal, are brought into contact with the wire ends 12 and clamp them securely in place in operation of the improved terminal, as will become apparent.

The tubular terminal block 14 is of generally rectangular cross-section and comprises a top wall 20, a front wall 22, a rear wall 26 and a bottom wall 24. The top wall 20 and the front wall 22 are centrally partially cut away so as to define a window 28 in the terminal block, provided so that an assembler may view the connecting wire ends 12 when wiring the terminal. A pair of tapped holes 30 are formed in the top wall 20 of the terminal block, and are of such a diameter as to form internal threads 31 in the front and rear walls, thereby insuring a secure threaded anchoring for the screws 16.

Threadedly engaged in the holes 30 are screws 16 having the kerfed screw heads 32 and threaded shanks 34. Each shank 34 is provided with a plain undercut portion 36 and a retaining flange 38 on its end opposite its head which is of larger outer diameter than the portion 36, but smaller than the shank 34. A sheet metal pressure pad, generally designated as 18, is carried by each screw shank.

Each pressure pad comprises: a pressure transmitting bottom wall 40; an upstanding wall portion 42 bent normal to bottom wall 40; deflecting mounting arms 44 bent normal to the upstanding wall, and inwardly bent limit ends 46, each describing an acute angle with its associated deflecting arm 44 and thereby terminating in camming surfaces 48. Each pressure pad 18 is arranged to be mounted upon and carried by a screw 16 in such a manner that its deflecting arms 44 straddle the undercut portion 36 of the screw shank and are seated between the larger diameter shank 34 and retaining flange 38. Since the inwardly bent ends 46 are formed so as to provide a clearance which is less than the diameter of the undercut portion 36 of the screw, it can readily be seen that the deflecting arms 44 must be forcibly flexed outwardly, away from one another, when mounting a pressure pad upon a screw. This outward flexing of the deflecting arms 44 is automatically accomplished during mounting of a pad as a result of the coaction of the camming surfaces 48 of the inwardly bent ends 46 with the undercut portion 36 of the screw shank when the pressure pad 18 is snapped into place. The snapping ac-

tion results in a screw mounting that insures that the pressure pad cannot be inadvertently lost or removed. The free end edges of ends 46 prevent such removal by digging into the portion 36, unless the legs 44 are intentionally separated.

When assembling the electrical wiring terminal of the present invention, the screws 16 are individually inserted into and threadedly engaged in openings 30 so that the undercut portion 36 of the screw shank is located on the interior of the terminal block 14. During such insertion, retaining flanges 38 freely pass through openings 30. Then the pressure pad 18 is slipped longitudinally in and through an open end of the terminal block, and the deflecting arms are aligned with and snapped about the undercut portion 36. With the pad thus rotatably seated on the end of the screw shank, the bared stranded ends 12 of the cable 10 may be inserted longitudinally in the tubular terminal block and disposed adjacent bottom wall 24, and the screws 30 are further threadedly advanced into the terminal block until the bottom walls 40 of the pressure pads are brought to bear on the wire ends 12 to firmly clamp them in position against bottom wall 24, which then constitutes a clamping wall. It can be clearly seen that as the screws 30 are rotated, the pressure pads 40 mounted thereon will not rotate but will merely exert a downward force on the wire ends. Therefore, in clamping the wire ends in the terminal, the action of the pressure pads is such as to produce effective compressive clamping without undesirable twisting of the wire ends.

Although the improved clamping screw and pressure pad means of the present invention has been described in use in a terminal block assembly, it will be understood that I have not comprehended to limit its use to such an environment. On the contrary, this improved clamping screw has application in innumerable electrical wiring terminal uses wherein a screw may be threadedly mounted in position to clamp a conductor wire end against a terminal clamping wall.

It is understood that the present disclosure has been made only by way of example and that numerous changes in details of construction and the combination and arrangement of parts may be resorted to without departing from the spirit and scope of the invention as hereinafter claimed.

What I claim as new and desire to secure by Letters Patent of the United States is:

1. For use in an electrical terminal having a terminal clamping wall, and a threaded opening means for supporting a threaded clamping screw in position to clamp a conductor wire end against the clamping wall, an improved clamping screw comprising: a threaded shank; a head at one end of said shank; a plain undercut portion, at the end of said shank opposite said head, of smaller diameter than said shank and terminating in a larger diameter retaining flange which is of smaller diameter than said shank; and a pressure pad mounted on said shank including a planar pressure wall disposed in front of said flange, a wall portion disposed substantially normally to said pressure wall, and a mounting means therefor including a plurality of deflecting arms disposed substantially normally to said wall portion and overlying said pressure wall, each arm having its major width di-

5 mension extending in a direction normal to the plane of said pressure wall and its minor width dimension extending in the direction of deflection, and securing means positioned at the ends of said arms, whereby said pressure pad may be operatively associated with said undercut portion so as to be mountable thereon by relative lateral movement of said mounting means and said undercut portion.

2. An improved electrical wiring terminal comprising: threaded opening means; at least one clamping wall portion; at least one clamping screw as defined in claim 1 arranged to be threadedly engaged in said threaded opening means with said pressure pad disposed to move toward and away from said clamping wall portion.

3. The improved electrical terminal clamping screw defined in claim 1 wherein said pressure pad is constructed of spring metal.

4. For use in an electrical terminal having a terminal clamping wall and a threaded opening means for supporting a threaded clamping screw in position to clamp a conductor wire end against the clamping wall, an improved clamping screw comprising: a threaded shank; a head at one end of said shank; a plain undercut portion, at the end of said shank opposite said head, of smaller diameter than said shank and terminating in a larger diameter retaining flange which is of smaller diameter than said shank; and a pressure pad mounted on said shank and including a planar pressure wall, a wall portion disposed substantially normally to said pressure wall, and mounting means including a plurality of deflecting arms disposed substantially normally to said wall portion and overlying said pressure wall, said deflecting arms being provided with camming portions at their ends, said camming portions being directed toward each other and forming acute angles with said deflecting arms.

5. The improved electrical terminal clamping screw defined in claim 4 wherein said pressure pad is constructed of spring metal.

6. An improved electrical wiring terminal comprising: threaded opening means; at least one clamping wall portion; at least one clamping screw as defined in claim 5 arranged to be threadedly engaged in said threaded opening means with said pressure pad disposed to move toward and away from said clamping wall portion.
